UNITED STATES PATENT OFFICE.

RICHARD HENRY COTTER, OF BROOKLYN, NEW YORK.

GAME.

Application filed April 8, 1922. Serial No. 550,846.

To all whom it may concern:

Be it known that I, RICHARD H. COTTER, a citizen of the United States, and a resident of the city of New York, borough of Brooklyn, in the county of Kings and State of New York, have invented a new and Improved Game, of which the following is a full, clear, and exact description.

This invention relates to improvements in games, particularly to a baseball game, an object of the invention being to provide a device of this character which will be interesting and amusing to all devotees of the national sport, and a game which will be simple and practical in construction, neat and attractive in appearance, and comparatively inexpensive to manufacture.

With these and other objects in view, the invention consists in certain novel features of construction and combinations and arrangements of parts as will be more fully hereinafter described and pointed out in the claims.

In the accompanying drawings:

Figure 1 is a top plan view of my improved game board, a portion of the game board being broken away for clearness;

Figure 2 is a view in longitudinal section through the game;

Figure 3 is a top plan view of the game with the game board or field and the grooved plate removed;

Figure 4 is a fragmentary detail view in section through one of the grooves; and

Figures 5 and 6 are similar views indicating the positions assumed by the indicators in the grooves as they are struck by a ball.

Referring in detail to the drawings, I have used the reference numeral 1 to designate a relatively shallow box. A grooved ball directing plate 2 formed of cardboard or other suitable material includes side flanges 3 snugly fitting within the walls of the box and a box cover 4 is provided with defining depending box embracing flanges 5.

Upon the cover 4 there is displayed a representation of a ball diamond, indicated by the reference numeral 6, and the box and cover are preferably shaped in substantially the same manner as a well laid out ball field, square openings 7 being provided in the game board to designate the four bases of the diamond.

The box is preferably supported in the

tilted or angular position, as shown in Figure 2, and at the upper end of the plate 4, there is provided a depression or pocket 8 into which a ball 9 is adapted to be delivered through an inclined shooting alley 10, extending below the plate and communicating with the pocket. The shooting alley or tube 10 is supported upon a transverse partition 11 in the bottom of the box, and balls dropped through the home plate opening 7 into the tube may be conveniently propelled through the tube and into the pocket 8 by a spring held shooting device or plunger 12. A series of grooves 13 through which the ball 9 is adapted to gravitationally roll are all in communication with the pocket 8 and a plurality of pins or other suitable interrupting devices 14 may be provided in the grooves, or in certain common entrances to a number of grooves to interrupt the gravitational travel of the ball and direct the same into any of the grooves. The extremity of each groove is located in registration with an opening 15 in the game board.

U-shaped indicators 16 normally supported upon their sides adjacent the extremities of the grooves 13 serve to normally conceal openings 17 in the bottoms of the grooves. These indicators likewise include upwardly extending fingers 18 projecting through the openings 15 of the game board. The indicators are preferably of a color which contrasts sharply with the color of the board so that as a ball gravitationally rolls down one of the grooves, it will strike the indicator, moving the same under one of the openings 15 to indicate a play. As the indicator is moved under the opening 15, the ball drops through the opening 17 and gravitationally rolls on the bottom of the box to an outlet opening 19 at its lowest point adjacent home plate. The finger 18 permits manual sliding of the indicator to its normal position ready for another play.

Although I need not necessarily be limited to this construction, I prefer to mount the tube 10 centrally of the field, that is, so that it extends from a point behind home plate to center field, where it terminates in a curved extremity 20 for delivering balls into the pocket 8. Suitable guide flanges 21 are provided in the bottom of the box for directing the ball toward the outlet opening 19.

after it has dropped through the grooved plate.

5 Adjacent each of the openings 15 of the game board there are displayed certain indicating letters 22, said letters indicating the play to be made upon the board when the ball rolls into the associated grooves. These letters, such as 1B for a single, 2B for a two-bagger, 3B for a triple, Home for a home 10 run, etc. corresponding to the plays, hits, put outs, strikes and balls of a ball game. A spinner 23 mounted centrally upon the diamond carries arms 24 upon which tokens 25, representing players are mounted. The 15 men on the end of the spinner are moved in accordance with the plays indicated by the indicators 16. The spinner preferably includes a depending central stem 26 projecting through the box cover and plate 4 20 and carrying a pinion 27. A rack bar 28 mounted in brackets 29 fixed to the tube 10 is engageable with the pinion and may be operated by a handle 30 extending through the wall of the box to turn the spinner. 25 Openings 25 in the field receive men representing the team in the field.

In playing the game, a ball is dropped through the home plate opening into the tube 10 and shot through the tube into the 30 pocket 8 from which it will gravitationally roll into any of the grooves 13. As the indicator at the lower end of this groove moves to indicate the play to be made, the spinner may be turned carrying the representation of a player into the proper position on the diamond. Of course certain of the plays, indicating strikes and balls will not necessitate turning of the spinner, while other plays, such as put outs, sacrifice hits, 35 etc. will necessitate the removal of one or more men from the spinner. The game is played just like an ordinary ball game, one side taking the field after three men have been put out and the other side going to bat.

40 I previously suggested that the grooved plate 4 might be made of pressed cardboard, but it is to be understood that any suitable material might be utilized in the construction of the game, any arrangement of 45 grooves might be employed, the design of the field might be changed, and numerous other slight alterations might be made in the general form and arrangement of the parts described without departing from the 50 invention, and hence I do not wish to limit myself to the precise details set forth, but shall consider myself at liberty to make such slight changes and alterations as fairly fall within the spirit and scope of the appended 55 claims.

The small rounded portions 16' on the bottom of the indicators which normally seat in the openings 17 to hold the indicators in place, may be dispensed with if desired. 60 These rounded depending portions

lift out of the openings when the indicators are struck by a ball due to the size and flexibility of the indicators.

I claim:

1. In a base ball game, a playing field, tokens movable on the field to indicate plays, a grooved plate under the field, a shooting alley under the plate, means for projecting a ball through the alley and onto the plate, said ball adapted to gravitationally roll into any of said grooves, means in the grooves indicating the presence of the ball therein, indicia associated with said indicators directing the movement of the tokens when the ball rolls into any groove, said grooves having openings therein normally covered by the indicators, and through which the ball is adapted to drop after an indicator has been moved to indicating position, said field having openings therein adapted to expose the indicators as they are moved by the ball.

2. In a base ball game, a playing field, tokens movable on the field to indicate plays, a grooved plate under the field, a shooting alley under the plate, means for projecting a ball through the alley and onto the plate, said ball adapted to gravitationally roll into any of said grooves, means in the grooves indicating the presence of the ball therein, indicia associated with said indicators directing the movement of the tokens when the ball rolls into any groove, said grooves having openings therein normally covered by the indicators, and through which the ball is adapted to drop after an indicator has been moved to indicating position, said field having openings therein adapted to expose the indicators as they are moved by the ball, and fingers on the indicators extending through the openings in the field for manually restoring them to their normal position.

3. In a base ball game comprising a member having representation of a base ball field including a diamond pictured thereon, a group of apertures arranged in each of the fields, each of said apertures representing a particular play, a guiding means connecting each of said apertures with a common opening, a spherical element and means for projecting said element in the common opening from which said spherical element will be guided to one of the apertures, playing pieces, a means rotatably supported on the diamond and having arms extending to the bases for carrying the playing pieces whereby the said means is moved in accordance with the play indicated by the element in the field in which the spherical element is

110 positioned, to indicate the base running of the playing member carried by the rotatably supported means.

4. A game comprising a top having the representation of a base ball field including

- a diamond arranged thereon, apertures arranged on the diamond at the positions corresponding to the bases thereof, other apertures arranged in the respective fields, said last named apertures being of a different shape, and being marked to represent different plays, a member rotatably supported on the diamond at a position corresponding to the pitcher's box and having arms extending therefrom to the respective bases, playing pieces, means for carrying one of said pieces on the arms, means arranged below the said top and having guiding grooves terminating in pockets arranged under and 10 in alignment with play indicating apertures, the other end of said grooves terminating in a common enlarged section, interference means arranged within said section, a spherical element, means for elevating the 15 end of the game on which the enlarged section is positioned, and means for projecting said spherical element into said common enlarged section and in engagement with said interference means which determines the 20 movement of said spherical element into one of the grooves where it comes to rest in one of the pockets indicating a certain play, said rotatably supported means being then manipulated in accordance with the indicated 25 play.
5. In a game apparatus, a playing field, a plate positioned beneath said field and having therein a pocket arranged adjacent one end thereof, and a plurality of grooves 30 all communicating with said pocket and extending toward the other end of the plate, indicating devices disposed in the latter ends of said grooves and projecting through said playing field, a propelling mechanism located beneath said plate, a guide extending from said propelling mechanism to said pocket, and an actuator for said indicating devices projected by said propelling mechanism into said pocket and into any one of 35 said grooves to actuate the indicating device therein.
6. In a game apparatus, a playing field, a plate positioned beneath said field and having therein a pocket arranged adjacent one end thereof, and a plurality of grooves 40 all communicating with said pocket and ex-
- tending toward the other end of the plate, indicating devices disposed in the latter ends of said grooves and projecting through said playing field, means projectable from the end of said plate remote from said pocket into said pocket and movable into any one of said grooves to actuate the indicating device therein, and propelling means for the last-named means. 45
7. In a game apparatus, a playing field having a plurality of openings therein, a plate positioned beneath said field and having a plurality of grooves therein, an indicating device movable longitudinally in each of said grooves and having a portion extending through an adjacent opening in the playing field, and chance controlled means movable into any one of said grooves 50 to actuate the indicating device therein. 55
8. In a game apparatus, a plate having a pocket positioned adjacent one end thereof and a plurality of grooves communicating with and diverging from said pocket, a playing field forming a cover for said plate and 55 grooves and having a plurality of openings therein each of which is disposed adjacent the end of a groove remote from said pocket, an indicating device movable in each groove and having a portion projecting through 60 the adjacent opening in the playing field, a projectile movable into said pocket and from thence into any one of said grooves for moving the indicating device therein, and means for propelling said projectile 65 into said pocket. 70
9. In a game apparatus, a playing field, a plate positioned beneath said playing field and for which said field provides a cover, said plate having a pocket and a plurality of grooves therein communicating with and diverging from said pocket, a guide extending beneath said plate and having a portion projecting into said pocket, a propelling device in said guide, means actuated by said propelling device to move along said guide and into said pocket and 75 from thence into any one of said grooves, and an indicating device in each groove actuated by the last named means to indicate 80 a play to be made. 85

RICHARD HENRY COTTER.
